UNITED STATES PATENT OFFICE

2,446,821

RESISTANCE-CAPACITANCE TUNED
OSCILLATOR

William Gassel, Philadelphia, Pa., and Henry Gritz, Iuka, Miss., assignors to Philco Corporation, Philadelphia, Pa., a corporation of Pennsylvania

Application December 30, 1944, Serial No. 570,678

2 Claims. (Cl. 250—36)

1

The invention relates to oscillation generators and more particularly to improvements in resistance-capacitance tuned oscillators.

As is well known, the tuning range for any one frequency band of a conventional resistance-capacitance tuned oscillator has a maximum to minimum frequency ratio of approximately ten-to-one. In order to generate oscillations over a wide frequency range, such as obtains from a practical wide range audio oscillator of this type, it is, at present, common practice to provide the oscillator with a sufficient number of frequency bands to cover the desired frequency span. To this end, there is usually included in the frequency-determining network of the oscillator several sets of resistors, together with a switching means for connecting a particular set of resistors in the network circuit for each frequency band.

It is evident that certain advantages procure from an oscillator whose frequency may be varied in a continuous and smooth manner over a wide range by one tuning control, rather than in a step-like fashion resulting from a plurality of frequency bands with the involved switching mechanism.

It is, therefore, the principal object of this invention to provide an improved resistance-capacitance tuned oscillator capable of generating a wide range of frequencies on one frequency band.

Another object of the present invention is to provide a novel and simple means whereby the usual tuning control of a resistance-capacitance tuned oscillator may vary the oscillator frequency over a wide range.

Another object of the present invention is to provide a novel wide range audio oscillator.

A further object of this invention is to provide a novel frequency-determining network for a wide range resistance-capacitance tuned oscillator.

Other objects and advantages of the present invention will become apparent during the course of the following description taken in conjunction with accompanying drawing in which

Fig. 1 shows schematically one embodiment of the present invention applied to one of the more common types of conventional resistance-capacitance tuned oscillators; and

Fig. 2 shows a modification.

In Fig. 1 of the drawing, that portion of the

5 circuit including the two-stage resistance-coupled amplifier represented by the block 1 and the regenerative coupling network composed of resistors R₁ and R₂ and variable condensers C₁ and C₂ comprises one form of a conventional resistance-capacitance tuned oscillator. Since the oscillator frequency depends upon the resistance of resistors R₁ and R₂ and the setting of variable condensers C₁ and C₂ the above network is often referred to 10 as the frequency-determining network. In accordance with usual practice, the amplifier should preferably be provided with a suitable inverse feedback and amplitude control circuit to insure an oscillator output having good wave form. In 15 practical oscillators of this type, the two resistors R₁ and R₂ are usually of the same value, and the two variable condensers C₁ and C₂ are similar and are ganged as illustrated in the drawing.

For each value of resistance for resistors R₁ 20 and R₂, the frequency of the oscillator may be varied, by means of the tuning control attached to the ganged variable condensers C₁ and C₂, over a band whose frequency ratio is about 10 to 1.

In accordance with the present invention, the 25 tuning control of a resistance-capacitance tuned oscillator is caused to vary the oscillator frequency over a considerably increased frequency range. This is accomplished by means of the series-connected resistance-capacitance elements 30 R₃C₃ and R₄C₄, which are respectively connected in shunt relation with resistors R₁ and R₂. Each of the condensers C₃ and C₄ is of small capacity, and the resistance of resistors R₃ and R₄ is low in comparison to that of resistors R₁ and R₂. As 35 the oscillator frequency is increased, the consequent decrease in the reactance of condensers C₃ and C₄ allows the resistors R₃ and R₄ to have more and more shunting effect upon the resistors R₁ and R₂ respectively, thereby lowering the 40 effective resistance across these latter two resistors. Variation of both the capacity and the effective resistance of the frequency-determining network during oscillator tuning permits the tuning control to govern the oscillator frequency over 45 a wide range of frequencies. By way of example, in an audio oscillator constructed in accordance with the embodiment of the invention illustrated in the drawing, a tuning range of 400 to 1 was attained. By selecting the proper element values 50 for each resistance-capacitance mesh R₃C₃ and

R₄C₄, a substantially flat frequency response curve, characteristic of conventional resistance-capacitance tuned oscillators may be obtained.

In practicing this invention in accordance with Fig. 1 of the drawing, the tuning control of the oscillator varied the frequency from 35 cycles per second to 14,000 per second with practically constant output when using the following circuit values:

Resistors R ₁ and R ₂	8.2 megohms each
Condensers C ₁ and C ₂	525 μf . each
Resistor R ₃	180,000 ohms
Condenser C ₃	75 μf .
Resistor R ₄	220,000 ohms
Condenser C ₄	60 μf .

It should be noted that this invention provides a means of calibrating the middle of the oscillator scale without affecting the calibration of the high or low ends of the scale. To this end, a padder condenser may be connected across capacitor C₃, as shown. It will be understood, of course, that this element is optional. The calibration of the oscillator at the high end of the scale may, of course, be accomplished in the usual manner by a padder condenser on variable capacitor C₁. Amplitude control may also be obtained in the usual manner by a padder condenser on variable capacitor C₂.

Although the invention has been described with reference to the embodiment shown in Fig. 1 of the drawing, it is to be understood that the invention is not limited to the particular values given by way of example, nor to the specific number and arrangement of the elements in the resistance-capacitance networks, represented in the drawing by R₃C₃ and R₄C₄. For instance, the values of resistance employed for resistors R₁ and R₂ may be such that the resistance of R₁ is considerably different from that of R₂.

Also, improvement in the wave shape of the output voltage and the frequency response characteristic of the oscillator over its wide frequency range may be obtained by connecting a resistor 2 across capacitor C₃, or by shunting a capacitor 3 across resistor R₁, or, preferably, by employing both as shown in Fig. 2. Resistor 2 should be of sufficient resistance to have minimum effect upon the lowest frequency desired from the oscillator. Condenser 3 should be of small capacity in order that the higher frequency range of the oscillator will not be affected. The improved wave form is occasioned by the increase in degenerative feedback which may be applied to the amplifier 1 as a result of the increase in regenerative feedback obtained through these additional elements.

With resistor 2 and capacitor 3 in the regenerative feedback circuit there is also an increase in the amplitude of the output voltage in the lower middle portion of the frequency range thus compensating for a drop of voltage occurring at this part of the range when these elements are not used. Aside from these additional elements, Fig. 2 is similar to Fig. 1.

It will thus be apparent to those skilled in the art that the present invention is capable of various embodiments or modifications which may be resorted to without departing from its scope.

We claim:

1. In an oscillator circuit, an amplifier, a regenerative coupling network connected between the output and input of said amplifier, said network including a resistor and a variable capacitor connected in series between the output and input of said amplifier, and also including a second resistor and a second variable capacitor connected in shunt relation across the input of said amplifier, and series-connected resistance and capacitance elements in shunt with each of said resistors and adapted to vary the effective resistance of said network in response to variation of the oscillator frequency, whereby to increase the frequency range of the oscillator.

2. In an oscillator circuit, an amplifier, a regenerative coupling network connected between the output and input of said amplifier, said network comprising a first branch including a resistor and a variable capacitor connected in series between the output and input of said amplifier and a second branch also including a resistor and a variable capacitor connected in shunt relation across the input of said amplifier, and series-connected resistance and capacitance elements in shunt with at least one of said resistors and adapted to vary the effective resistance of one of said branches in response to the variation of the oscillator frequency whereby to increase the frequency range of the oscillator.
